PREPARATION OF ARYL DICARBOXYLIC ACIDS

John L. Darragh and Robert J. Miller, Berkeley, Calif., assignors to California Research Corporation, San Francisco, Calif., a corporation of Delaware

Application October 4, 1947, Serial No. 777,970

9 Claims. (Cl. 260—515)

1

This invention relates to the preparation of aryl carboxylic acids in which a carboxyl group preferably is directly attached to the aromatic nucleus and involves the production of such aryl carboxylic acids from alkyl aromatic hydrocarbons and preferably from polymethyl-substituted aromatic hydrocarbons. More particularly the invention relates to a process for producing mono nuclear polycarboxylic acids, and in its preferred embodiment comprises a process for preparing isomeric phthalic acids, such as the terephthalic isomer.

Known methods for producing isomeric phthalic acids, such as terephthalic, have utilized indirect chemical syntheses which result in costs so high as to be prohibitive for large scale production. Certain more direct methods such as oxidation of para xylene with potassium permanganate or chromic acid require consumption of relatively expensive chemical reagents and likewise involve excessive costs.

An object of this invention is to provide a new and improved process for the production of aryl carboxylic acids and one which is of special advantage for preparing isomeric phthalic acids. Another object is to furnish an improved method for the synthesis of terephthalic acid.

Additionally, an object is to synthesize mono nuclear aryl polycarboxylic acids with low cost chemical reagents.

Another object is to produce terephthalic acid by a process which involves oxidation with caustic alkali. Further, an object is to provide a process capable of enhancing yields of carboxylic acids in the caustic oxidation of aryl methyl chlorides.

Other objects and advantages of the invention will be apparent from the drawing and the following detailed disclosure.

In accordance with this invention aryl carboxylic acids, particularly mono nuclear aryl polycarboxylic acids, are obtained by formation of polyalkyl aromatic chlorides in which a chlorine atom is attached to a primary alkyl carbon atom, and conversion of such chlorides to carboxylic acids by reactions involving oxidation with aqueous caustic alkali. Preferably, the chlorinated primary alkyl carbon atom is attached directly to a benzene nucleus, as in chlorides of para xylene:

2

However, the process is applicable to compounds such as

and their homologs. Corresponding derivatives of naphthalene and anthracene also may be utilized.

30 Briefly described a process embodying the present invention utilizes a combination of process steps involving:

(1) Formation of an aryl substituted primary alkyl chloride such as xylal chloride

35 (CH₃C₆H₄CH₂Cl)

xylyl chloride (CH₃C₆H₄CH₂Cl₂), xylylene dichloride (ClCH₂C₆H₄CH₂Cl), or mixtures thereof, either by chlorination of xylene or by chloromethylation of toluene or both;

(2) Separation of at least a xylylene dichloride fraction from the chlorinated reaction mixture;

(3) Conversion of the separated xylene chlorides to corresponding carboxylic acids by hydrolysis and oxidation with aqueous caustic alkali.

(4) Chlorination of at least a part of the resulting toluid acids to corresponding chloromethyl benzoic acids, and

50 (5) Conversion of chloromethyl benzoic acids

to the corresponding dicarboxylic acids by hydrolysis and oxidation with caustic alkali.

It should be noted that the chemicals consumed in the foregoing synthesis are chlorine and aqueous caustic alkali, each of which is a low cost bulk chemical. In chloromethylation formaldehyde also is consumed, and this likewise is a low cost bulk product. No expensive oxidizing agents are required. Also, it is important that chlorination to a single chlorinated product is not necessary to substantially complete conversion to phthalic acids.

Since the process of this invention finds its principal present application in the manufacture of terephthalic and/or isophthalic acids, the invention and process will be illustrated hereinafter by reference to the production of these isomeric phthalic acids from the xylenes and/or toluene. Special emphasis is herein given to the production of terephthalic acid from paraxylene.

In the drawing, Fig. 1 is a flow sheet illustrating in block diagram a process for converting para xylene to terephthalic acid or for obtaining a mixture of phthalic acids from toluene or for producing mixed phthalic with or without benzoic acid from xylene and toluene.

Fig. 2 is a graphical showing variation with temperature (in ° F.) of yield of terephthalic acid and terephthalic content of acids from caustic oxidation of chloromethyl benzoic acid.

Fig. 3 is a similar graph showing effect of temperature (in ° F.) on yield of benzoic acid from benzyl chloride.

Reference to the drawing will reveal that a xylene fraction such as para xylene is introduced by way of feed line 10 to a chlorination zone 11 where chlorine is introduced into the methyl side chains. The chlorination reaction is conducted under conditions which favor side chain chlorination and may result in the following reactions:

Tri- and polychlorinated compounds also may be formed. If minor amounts of ring chlorination occurs, the subsequent process steps still yield the desired compounds. The mixture of chlorinated products then passes as indicated by line 12 to a separation zone 13 and, as here shown, three fractions of chlorinated xylenes are obtained. Any suitable method of separation, such as distillation under relatively high vacuum (to minimize decomposition of the chlorides), may be used. When the hydrocarbon feed is para xylene, a para-xylyl chloride fraction, a para-xyl chloride fraction and a para-xylylene dichloride fraction are conducted as shown by lines 14, 16 and 17 respectively to further processing units. If benzyl chloride is formed from any toluene pres-

ent in the xylene feed, this chloride is removed by way of line 29. Lower boiling fractions, such as unchlorinated hydrocarbons, may be removed through outlet 30 and higher boiling compounds are withdrawn as indicated by line 35.

The para xyl chloride fraction from line 14 is converted to para toluic acid by reactions involving hydrolysis and oxidation of the hydrolyzed product to toluic acid.

25 These reactions may be effected either substantially concurrently or in two stages. As indicated in the flow sheet, a para xyl chloride fraction is hydrolyzed to para methyl benzyl alcohol in reaction zone 18 and the alcohol is converted to para toluic acid by caustic oxidation in reaction zone 19 which may be physically the same or different from zone 18. The acid may be recovered as the sodium salt.

30 Para xyl chloride is converted to para toluic acid in reaction zone 21 by hydrolysis and oxidation with caustic alkali. The reactions are:

50 After being converted from salt to the free acid the para toluic acid from zones 18 and 21 next is subjected to side chain chlorination to form chloromethyl benzoic acids by the reactions:

70 Side reactions also may occur, for example:

Minor chlorination in the ring is not precluded.

Although the para toluic acid may be chlorinated while dissolved in solvents such as carbon tetrachloride, better results have been obtained by direct chlorination of the molten acid, for example, at temperatures of from 190° C. to 270° C.

The foregoing conversion to chloromethyl benzoic acid is effected in reaction zone 22 from which the chlorinated products are conveyed as shown by line 23 to reaction zone 24 for conversion to terephthalic acid. In this reaction zone the chloromethyl groups are hydrolyzed and then oxidized by aqueous caustic alkali to a carboxyl group, thereby yielding terephthalic acid by the following reactions:

Corresponding reactions occur with dichloro methyl toluic and trichloro methyl toluic acids.

The reaction mixture containing terephthalic acid passes to product recovery zone 26. Any suitable method of recovery and purification may be used, for example, acidification, crystallization and washing with solvents.

When and if a mixture of xylenes is fed to chlorination zone 11, a corresponding mixture of ortho, meta and para xylene chloride isomers will be obtained. The product will therefore be mixed isomeric phthalic acids; but, if desired, a separation between para toluic acid on the one hand and meta and ortho toluic acids on the other hand may be effected, as by distillation. Two different phthalic acid products, namely a terephthalic acid and a mixture of ortho and meta phthalic acid, may then be produced from the two separated toluic acid fractions. After such a separation (not shown in flow sheet), the mixed ortho and meta toluic acid fraction may be withdrawn as indicated by line 27 from caustic oxidation zone 19. The resulting para toluic passes to zone 22 for chlorination as shown. The xylylene dichlorides may be separated in suitable fashion. Thus, because of its high melting point the para xylylene dichloride may be separated by crystallization. The ortho and meta isomers may be separated from each other by fractional distillation, preferably under vacuum to avoid decomposition.

Toluene which may be contained in the mixed xylene feed or separately introduced by way of valve-controlled line 28 will be chlorinated in zone 11 to form benzyl chloride which is conducted to separation zone 13 and withdrawn

therefrom as a benzyl chloride fraction indicated by line 29. The benzyl chloride fraction is converted to a mixture of xylylene dichlorides by chloromethylation in zone 31. The xylylene dichloride product is hydrolyzed to the corresponding glycol in zone 32 and the glycol converted to isomeric phthalic acids by oxidation with aqueous caustic alkali in zone 33.

In order to augment the supply of mixed xylene chlorides and provide a supplemental production of toluic acids and chloro toluic acids, toluene admitted by way of inlet line 34 may be converted to xylyl chloride by chloromethylation in reaction zone 36. The hydrogen chloride formed in xylene chlorination zone 11 together with formaldehyde is utilized as shown to effect the chloromethylation reaction. A mixture of ortho, meta and para xylyl chlorides from reaction zone 36 is passed by way of line 37 to separation zone 38. If desired the xylyl chlorides may be fractionated and a purified para xylyl chloride fraction removed from separation zone 38 by way of line 40. When a mixed xylene hydrocarbon feed is used for zone 11, only mixed chlorides need be separated in zone 38. Hydrolysis to methyl benzyl alcohol in reaction zone 18 and conversion to a mixture of toluic acids in reaction zone 19 is effected as previously disclosed. If and when it is desirable to synthesize a relatively pure terephthalic acid, the mixed toluic acids are fractionated to separate a para toluic product and leave a mixed ortho and meta toluic acid fraction as previously disclosed. The para toluic acid fraction will then be passed to chlorination zone 22 for conversion to para chloromethyl benzoic acid. The chloromethyl benzoic acid then passes as shown by line 23 to caustic oxidation zone 24 where it is converted to terephthalic acid in the manner hereinbefore disclosed.

The process of this invention and suitable modes of operation will be readily apparent in the light of the following illustrative data and examples.

In small scale operations, the chlorination reaction of zone 11 was carried out in glass reactor equipped with a sintered glass plate at the bottom through which gaseous chlorine was fed. The reactor when used for continuous chlorination was provided with an inlet line at the bottom, through which the hydrocarbon feed entered the reactor and an outlet line near the top for removal of reaction mixture at the same rate as hydrocarbon entered the reaction zone. Reaction temperatures were taken by a thermocouple extending into the reaction liquid. The reactor was topped by a water-cooled condenser through which exit gases were removed and absorbed in aqueous caustic. Vacuum distillations utilized for separating the xylene chlorides were carried out in distillation columns packed with glass helices and equipped with an electrically heated jacket. Liquid constituents of the reaction mixtures were removed through an ordinary water-cooled head. Para xylylene dichloride and other high melting constituents were taken off the fractionating column through a special head surrounded by a glass jacket containing boiling toluene to prevent solidification in the lines prior to reaching the storage receiver.

Chlorination in batch operation can be effected in the presence of light at approximately 95° C. This temperature may be varied from 40 to 130° C., for example. When theoretical quan-

tities of chlorine necessary to form a xylylene dichloride were passed into the reaction mixture, some dehydrohalogenation occurred both during chlorination and upon distillation of the chlorinated product under vacuum at 3-8 mm. mercury pressure. Continuous chlorination was carried out at about 95° C. in the presence of light with greatly improved results. Para xylene and chlorine were fed to the reactor at constant rates and excellent chlorine utilization obtained. Steady state compositions were obtained for each feed ratio in continuous chlorination by taking samples from the continuously withdrawn chlorinated product and analyzing for chlorine content. When chlorine content became constant, the reactor was assumed to be under steady state operation. In the data here given, chlorine contents were measured by saponification numbers.

Because of the many possible products, complete analysis of the chlorinated mixtures was not made, but several of the retained samples were analyzed by distillation at reduced pressure to give compositions of typical chlorinated reaction mixtures.

TABLE I

Distillation analysis of chlorinated p-xylene

Distillation No.	1	2	3	4
SAP No. mgKOH	129	274	278	371
Per Cent Chlorine gm	10.4	20.4	20.5	29.1
Results (Per Cent by Weight):				
p-Xylene	60.3	35.5	34.0	17.2
p-Xylyl Chloride	22.2	34.2	28.5	32.2
p-Xylylene Dichloride	2.0	13.5	14.0	22.2
High Boiling Material	14.0	4.4	2.0	5.0
Bottoms	4.6	9.8	17.6	
Loss	1.5	7.8	11.7	5.9

From the results of the foregoing distillations, it will be seen that as the chlorine to para xylene feed ratios are increased the yield of para xylylene dichloride increases.

A large batch of the reaction mixture of chlorinated compounds was treated for separation as follows: The chlorinated mixture was cooled in an ice bath and the crystals formed were filtered off. The filtrate was then charged to a still and unreacted para xylene and para xylyl chloride removed under vacuum. The still bottoms were dissolved in about half their volume of chloroform and the resulting solution cooled in an ice bath where additional crystals were recovered and combined with those first separated. These crystals, after purification by recrystallization from chloroform, were identified as para xylylene dichloride by chlorine content, melting point and hydrolysis to the para xylylene glycol derivative.

The mother liquor from the foregoing chloroform crystallization was concentrated to 50% of its volume and again cooled in an ice bath. A second fraction of crystals more soluble in chloroform than para xylylene dichloride was obtained and recrystallized from a mixture of petroleum ether and benzene. These crystals were identified as para xylyl chloride by their chlorine content and melting point and by the fact that hydrolysis yielded para talualdehyde rather than the glycol.

After separation of the chlorinated reaction mixture to yield a xylyl chloride fraction, a xylyl chloride fraction and a para xylylene dichloride fraction, these respective intermediates are treated for conversion to the corresponding carboxylic acids or sodium salts thereof.

CONVERSION OF XYLYL CHLORIDE

A preferred mode of operation involves simultaneous hydrolysis and oxidation of xylyl chloride to the corresponding toluic acid at 300° C. to 400° C. (575-750° F.). The overall reaction may be written:

However, it may be effected in two stages:

A single stage operation presently is regarded as most desirable. The reaction may be effected by agitation in a rocker type autoclave under the following conditions:

Time, hours	1
Temperature, °C	371
Caustic concentration, percent	8
NaOH, moles	2
Xylyl chloride, moles	1
Yield of toluic acid (moles per mole of xylyl chloride)	.85

XYLYL CHLORIDE CONVERSION

Xylyl chloride is converted to the corresponding toluic acid by hydrolysis and oxidation preferably at 300° C. to 400° C. (575-750° F.). These reactions may be effected by agitation in rocker type autoclave as follows:

Time, hours	1
Temperature, °C	371
Caustic concentration, percent	10.9
NaOH, moles	3
Benzal chloride, moles	1
Yield of benzoic acid, moles per mole of benzal chloride	.91

CONVERSION OF XYLYLENE DICHLORIDE

In small scale runs for this stage of the process reactions were carried out in a rocking autoclave capable of withstanding pressures up to 16,000 pounds per square inch gauge and constructed entirely of Monel metal. The head of the vessel was fitted with a thermocouple, a safety valve, vent, a pressure gauge and a sample valve. Heat was supplied through strip heaters located in the autoclave casing. The whole assembly was agitated by rocking in a vertical plane with a maximum deviation from the horizontal of 30° and at a rate of 78 cycles per minute.

The desired material was charged to the autoclave together with a predetermined amount of caustic soda, water and the oxidizing agent when one was used. The vessel was lock-closed, placed in a shaker casing, and if a gaseous oxidizing agent such as air or oxygen was to be used, it was

charged at this time through the sample valve. The amount of oxidizing agent was calculated from the total pressure and known free-space in the vessel.

Heat was turned on and shaking started. After reaching reaction temperature, the mixture was allowed to react for one hour while controlling the temperature to maintain it substantially constant. At the end of one hour reaction time (exclusive of heating and cooling periods), shaking was stopped, heat turned off and the apparatus allowed to cool overnight. Upon removal of the cooled reaction mixture from the autoclave, it was filtered to remove dirt and traces of insoluble by-products and next acidified to a pH of 3.0 with HCl to convert the salts back to free acid which forms a precipitate. The precipitated acid was recovered by filtration, washed free of chloride ion, dried and weighed. A sample of the dried product was dissolved in a standard base solution, back-titrated potentiometrically with standard acid and the acid number obtained. Yield was calculated from these data.

Pure para xylene dichloride when reacted with four or more mols of caustic soda per mol of the dichloride at 371° C. (700° F.) for one hour yields a terephthalic acid product containing impurities. Yields and impurity contents are illustrated by the following table of data:

TABLE II
Caustic oxidation of xylylene dichloride

Mols Zyllyene Dichloride Charged	Mols NaOH Used	Conc. NaOH Solution, Per Cent	Conv. Based on Chloride, Per Cent	Wt. Per Cent of By-Product Based on Charge	Wt. Yield of Acids Based on Charge, Per Cent	Acid No. of Product mg. KOH per Gram
0.50	2.0	8.1	100	1.0	65	452
0.50	2.0	8.1	100	-----	53	410
0.50	2.0	8.1	100	2.3	66	423
0.50	2.0	8.7	100	1.7	64	427

The by-product on which approximate percentages are given above is a neutral, pasty material insoluble in aqueous caustic. The acid numbers shown in the foregoing tables were obtained on the crude chloride-free acidic reaction products. Acid numbers can be raised to from about 500-512 in all cases by recrystallization from water. The significance of acid numbers is illustrated by theoretical acid numbers as follows:

Toluic acid	412
Terephthalic acid	672

Pure terephthalic and pure toluic acids were isolated from the reaction mixtures and identified by means of acid number and methyl ester. In addition a water insoluble neutral material was found to be present and is removed by filtration of aqueous solutions during recrystallization. The foregoing reaction is believed to occur step-wise as follows:

In any event it has been found that terephthalic acid can be prepared from para xylylene glycol by subjecting the glycol to caustic oxidation at 371° C. (700° F.) for one hour as in the conversion of para xylylene dichloride. The product from the caustic oxidation of para xylylene glycol contained a neutral product, paratoluic acid, and terephthalic acid substantially as in the previous preparation from para xylylene dichloride. The xylylene glycol was obtained for this reaction by hydrolysis in a dilute water solution at reflux temperature followed by extraction with ether to recover the glycol from the aqueous medium.

Important variables were investigated to determine their effects upon the foregoing caustic

oxidation reactions. Among the factors investigated were: effect of concentration of the xylene chloride in the caustic, effect of concentration of caustic and of excess proportions of the caustic solution on the product, effect of time and temperature of reaction, and effect of oxidising reagents. Each of these factors is discussed hereinbelow.

EFFECT OF CONCENTRATION ON CONVERSION OF XYLYLENE DICHLORIDE

55 A decrease in concentration of the xylylene dichloride increases the acid number of the product and reduces the amount of neutral by-product. The weight yield of the product remains substantially constant and the concentration as well as the amount of excess caustic over theoretical appeared to have no effect on the product within the limits investigated. The following series of data in which the reactions were conducted at 700° F. with one hour reaction time are illustrative:

TABLE III
Oxidation of varying concentrations of xylylene dichloride to terephthalic acid

Effect of temperature, time, and pressure on xylene dichloride conversion.—A temperature between 315–371° C. (600–700° F.) yields a product of a fairly constant acid number. As temperatures increased above 371° C. (700° F.) or reaction times are prolonged, or both, the yield of total acid drops off. Thus, it appears that about 315° C. (600° F.) is as high a temperature as is necessary and that reaction times in excess of one hour achieve little or no benefit. However, the process is operative at temperatures of from 250° C. to 400° C. (480–750° F.). Illustrative data are given in the following table:

TABLE IV
Oxidation of xylene dichloride-variable time and temperature

Pressure is not critical except that it should be sufficient to maintain the aqueous caustic in liquid phase.

Effect of oxidizing agents on conversion of xylene dichloride.—It has been found that use of an oxidizing agent, such as air, achieves a marked improvement in yields and purity of the terephthalic acid product. In fact, substantially theoretical yields of nearly pure terephthalic acid have been obtained by intimately contacting the reaction mixture of aqueous caustic and xylene chlorides with air. The data in the table below exemplify the excellent results obtainable.

turbo-mixer equipped with a mercury-sealed stirrer. Chlorine was introduced at the bottom of the reactor which was immersed in an electrically heated oil bath. The chlorine was pre-heated in a coiled feed line immersed in the oil bath and leading to the bottom of the reactor. Exit gases from the reaction mixture pass through a side-arm to a condenser. The toluic acids tend to sublime and plug air condensers. To alleviate this tendency an oil heated condenser was attached to the reactor and an air-cooled condenser in turn attached to the outlet of the oil heated condenser. Exit gases, thus,

first passed through the oil condenser where a major proportion of any sublimed acids were condensed, melted and returned to the reactor. The remaining gases next flowed to the air condenser and were led to a caustic absorber for extracting HCl and residual acidic products carried thereby.

Although para toluic acid, for example, may be chlorinated in boiling carbon tetrachloride in the presence of light, direct chlorination of molten toluic acids yields better results. The toluic acid is charged to the reactor, melted, heated to the desired temperature and there-

CONVERSION OF TOLUIC ACIDS

Returning now to the intermediate toluic acids, it will be recalled that, in addition to use as such, these compounds may be converted to their corresponding phthalic acids by chlorination in the methyl group and caustic alkali oxidation of the resulting chloromethyl benzoic acid (α -chloro para toluic acid). Each of these stages will be described.

Chlorination of toluic acids.—The direct chlorination of toluic acids was carried out in a glass

after contacted with gaseous chlorine under constant agitation. Temperatures of from 190° C. to 270° C. are suitable conditions. While chlorination of para toluic acid to form para methyl benzoic acid is a preferred aspect of the invention since a main objective is to produce terephthalic acid, it was found that all three isomers of toluic acid will undergo direct side-chain chlorination in the molten state. Ortho toluic acid gave a 13.7% chlorine-containing product, for example; and two runs with meta toluic acid yielded products containing 16.8 and 19.1% chlorine respectively. Various runs made with para toluic acid and data on results obtained are given in Table VI:

Attention is directed to the fact that in Table IV, Example No. 8 shows that reduction of temperature decreased dehydrohalogenation and at the same time increased chlorine utilization as well as the chlorine content of the product. The extent to which the temperature may be lowered is limited by the fluidity of the reaction mixture which contains some high melting components. From the data in Table VI, it also appears that oxidation occurs under the chlorination condi-

25 The para chloromethyl toluic acid desirably is converted to terephthalic acid in a single stage caustic oxidation process by contacting with aqueous caustic at 150-400° C., for example at 315° C. (600° F.). The following examples are

30 illustrative and show that chlorine content of the feed within the ranges tested has no profound effect upon the acid number of the product. A large excess of oxygen diminished the weight yield of product.

tions. While some of the para toluic acid charge stocks contained terephthalic acid, the amount therein is insufficient to account for the high acid number of the products. Extraction of the chlorinated products with 190 proof alcohol (in which terephthalic acid is insoluble) yielded an alcohol soluble portion and an alcohol insoluble portion having acid numbers of 366 and 522, respectively. Accordingly, it is believed that the chlorine serves as an oxidizing agent to convert a portion of the para toluic acid to terephthalic acid by an oxidation reaction which is presently not understood.

On comparing sample 10 with samples 8 and 9, it appears that removal of impurities from the crude toluic acid by caustic purification or distillation achieves substantial improvements in chlorine utilization, and in yields and purity of product.

Conversion of para chloromethyl benzoic acid.—

The effect of different variables on the single stage conversion of para chloromethyl benzoic acid was investigated.

Effect of temperature on conversion of chloromethyl benzoic acids.—Effect of temperature is decided in altering yields of total acids as well as per cent terephthalic acid in the reaction product. The effect of changes in temperature on total weight of acids and on the percentage of terephthalic in the acid reaction products is illustrated graphically in Fig. 2 based on the data of Table VIII. Yield drops rapidly below 200° C. (400° F.) and little benefit is apparent above 315° C. (600° F.). Temperatures of 150-400° C. are operative. The data in Table VIII were obtained in small scale runs in which reaction time was one hour and charge stock contained 78% of theoretical chlorine for para chloromethyl benzoic acid.

Effect of concentrations on conversion of chloromethyl benzoic acid.—The foregoing runs were performed with the chlorinated toluic acids present in dilute solution and with a high molar excess of caustic soda. Additional tests revealed that the reaction can be effected with good yields and relatively high efficiency at high concentrations of the chlorinated acids and without large excess of caustic soda. Illustrative data are given in Table IX:

¹ This experiment was made on a chlorinated crude toluic acid.

In the foregoing tests, oxygen was substituted for air so that lower pressures could be utilized.

Effect of oxidizing agents.—Except where otherwise noted, oxygen in the form of air was used for all of the reported examples on the conversion of para chloromethyl benzoic acid. It has been found that quantities of oxygen less than one mol per mol of para chloromethyl benzoic acid, although operative, result in loss in conversion of terephthalic acid and yield reaction products having lower acid numbers. A slight excess of oxygen is preferred as will be apparent from the following data:

their corresponding phthalic acids by caustic oxidation at temperatures within the range of 150-400° C., e. g. at 315° C. (600° F.), for a reaction period of one hour in a manner similar to the foregoing examples with para chloromethyl toluic acid. The invention and condition for reaction as herein disclosed is applicable to the ortho and meta isomers as well as to the para product.

Effect of caustic concentration.—Relatively di-

lute solutions of caustic alkali in water are preferred for the oxidation reactions herein disclosed. Good results have been obtained over the range of from 4 to 10% by weight of caustic soda and it was evident that higher concentrations as well as somewhat more dilute solutions are operative.

CONVERSION BY CHLOROMETHYLATION

55 Utilization of by-product HCl by chloromethylation of toluene or of benzyl chloride (produced by chlorination of toluene contained in or added to the xylene feed) has been shown in the de-

Ortho chloromethyl toluic acid and meta chloromethyl toluic acid have been converted to

scription of the flow sheet of Fig. 1. This type of reaction will be illustrated in connection with the

chloromethylation of benzyl chloride to form para xylylene dichloride. The reaction

is carried out in the presence of a condensation catalyst such as zinc chloride, hydrogen fluoride, or aluminum chloride. The tendency of benzyl chloride to react with itself may be reduced by feeding the benzyl chloride to an excess of the reaction mixture and by such other expedients as will occur to those skilled in the art.

The process is illustrated by small scale examples in which benzyl chloride, formaldehyde, catalyst, and solvent were mixed and contacted with HCl for a period of several hours. The reaction mixture was allowed to stand overnight, washed, dried and filtered. Solvent and unreacted benzyl chloride were removed by distillation and the dichloride was recovered by crystallization. Data and results of these runs are given in Table XI:

¹ Catalyst prepared by fusing 210 gm. of $ZnCl_2$ and stirring in 10 gm. of $AlCl_3$ as it cooled.

² Yields are based on the amount of formaldehyde used.

The xylylene dichloride may be converted to corresponding phthalic acid by either a single stage caustic oxidation or by first hydrolyzing to form the xylylene glycol and then oxidizing to the dicarboxylic acid. Although a single stage conversion usually is preferred, conditions for a two-stage process will be illustrated. In the first stage xylylene dichloride is subjected to hydrolysis in dilute water solution at refluxing temperature. The xylylene glycol is recovered by ether extraction of the reaction solution. In the second stage the recovered glycol is subjected to caustic oxidation by intimately contacting the glycol with air or oxygen and an aqueous caustic solution at, for example, 371° C. (700° F.) for one hour as disclosed in the various processes for converting the chlorides to the acids. The resulting product will be a mixture of para toluic acid and terephthalic acid which can be separated in any suitable manner as by distillation. If desired, the para toluic acid may be passed to a chlorination stage for conversion to para chloromethyl benzoic acid after which a caustic oxidation will serve to form terephthalic acid therefrom.

Xylyl chloride is obtained from toluene by chloromethylation in a manner analogous to the chloromethylation of benzyl chloride. Exemplary conditions are:

Ethylene dichloride, ml. 500
Toluene, moles 1
Zinc chloride, gr. 68

Paraformaldehyde, equivalents 1
HCl gas bubbled through for 8 hours at 50° C.
Reaction mix allowed to stand overnight, washed, dried, and filtered. Reaction products separated by fractional distillation at reduced pressure.

The resulting product may be converted to toluic acids as hereinbefore disclosed.

From the foregoing it will become apparent that the combination of process steps herein disclosed affords a method for obtaining substantially complete conversion of a xylene, toluene or analogous methyl-substituted aromatic hydrocarbon to corresponding carboxylic acids with high yields while avoiding the necessity for complete chlorination to theoretical dichloride content. It is unnecessary to obtain maximum yield of the xylylene dichloride, for example, in order to produce dicarboxylic acids thereby permitting under-chlorination with resulting higher selectivity for side-chain chlorination as against ring chlorination while simultaneously minimizing over-chlorination in the side chain with attendant higher overall chlorine and caustic consumption. The

invention also furnishes a process for completely converting a mixture of chlorinated methyl benzenes, such as xylenes, to carboxylic acids notwithstanding that the degree of chlorination or the number of chlorine atoms per molecule of xylene varies widely. Despite this variation in chlorine content, production of corresponding carboxylic acid salts may be effected in single stage conversions. The process also is adapted to produce polycarboxylic acids from the under-chlorinated compounds by further chlorination and conversion of any monocarboxylic acids from the foregoing single stage conversions. The process enables economical utilization of by-product HCl produced in the chlorination reactions. It is important that terephthalic and the like acids are obtained by this invention with relatively cheap bulk chemicals, such as caustic soda, chlorine and, when desired, formaldehyde.

The benefits of various features of this invention are applicable to the caustic oxidation of benzyl chloride, benzyl alcohol or benzaldehyde to benzoic acid. This is especially true concerning the use of air or gaseous oxygen to increase the yield of acid produced. For example, in comparing runs made at 371° C. (700° F.), 3800 pounds per square inch, and a reaction time of one hour, it was found that by utilizing two mols of caustic in 8% aqueous solution per mol of benzyl chloride without addition of air or oxygen, about 88% yield of benzoic acid was obtained with about 8% by-product. In a second run at

371° C. (700° F.) at the same pressure and reaction time, the results were as follows:

Benzyl chloride reacted, mols.....	0.107
NaOH used, mols.....	0.225
Solution strength, percent.....	2
Mols of O ₂ (as air).....	0.12
Mol yield of acids, percent.....	96
Mol yield of by-product, percent.....	4

Intimate contact of the gaseous oxygen with the liquid reactants was obtained by vigorous agitation. It will be observed that the presence of this oxidizing agent reduced the amount of by-product formed from about 8 to 4%, a factor of approximately one-half.

The effect of temperature on caustic oxidation of benzyl chloride to benzoic acid is illustrated by the following discussion and data.

Fig. 3 reveals that reduction of temperature below 340° C. (650° F.) decreases yield of acid but does not render the process inoperative. Optimum reaction temperature for conversion of benzyl chloride to benzoic acid is in the range of from 370-400° C. (700-750° F.).

When either benzyl alcohol or benzaldehyde was substituted for the benzyl chloride under exactly the same reaction conditions as were used for the benzyl chloride conversion, somewhat higher yields of the acid were obtained. Table XII gives data on such substitutions:

TABLE XII

Charge Oxidized	Mols Charged	Mols NaOH	NaOH Solution, Per Cent	Mol Yield Benzoic Acid, Per Cent	Mol Yield By-Product, Per Cent
Benzyl alcohol	1	1	8	93	4
Benzaldehyde	1	1	8	95	4

Suitable temperatures for conversion of benzaldehyde and benzyl alcohol to benzoic acid by this reaction are 300 to 400° C.

Air or gaseous oxygen is advantageously used as an oxidizing agent in the foregoing reactions. Caustic oxidation of benzyl chloride, benzyl alcohol and benzaldehyde all produce the same by-product, mainly, benzyl ether, and in the case of benzyl chloride some unreacted benzyl alcohol. These by-products may be recycled to main reaction zone in order to suppress further formation thereof and increase the yield of acid.

Reference has been made to the fact that when and if ring chlorination occurs as a side reaction, the desired carboxylic acid is nevertheless obtained. This factor is believed highly significant to the good yields and superior purity of the products herein obtained. Under the caustic oxidation reaction conditions herein disclosed, the chlorine in the ring is removed and converted to HCl initially, which is of course neutralized by the caustic yielding a desired carboxylic acid. The removal of such ring chlorine is illustrated in conversion of chloro benzyl chloride to benzoic acid in which the following reaction occurs:

Analogous reactions occur with xylyl, xylal and xylylene chlorides containing chlorine in the ring as well as in the side chain.

Although the caustic alkali herein utilized for purposes of illustration has been sodium hydroxide, other strong alkali hydroxides such as potassium hydroxide may be substituted therefor. Likewise other modifications and variations of the invention as hereinbefore set forth may be made without departing from the spirit and scope thereof, and only such limitations should be imposed as are indicated in the appended claims.

We claim:

1. A process for producing benzene carboxylic acids which comprises oxidizing a xylene having at least 1 and not more than 2 chlorine atoms substituted in each methyl group by contact with aqueous caustic alkali in an oxidation zone at a temperature in the range about 300 to 400° C. under a pressure sufficient to maintain the aqueous caustic alkali in liquid phase to form a reaction product comprising benzene carboxylic acid salts and hydrogen.
2. The method as defined in claim 1, wherein a free oxygen-containing gas is introduced into the oxidation zone at reaction temperature to consume produced hydrogen.
3. The method as defined in claim 2, wherein the chlorinated xylene consists predominantly of xylene dichloride.
4. The method as defined in claim 1, wherein the chlorinated xylene consists predominantly of xylene dichloride.
5. A process of producing a benzene dicarboxylic acid which comprises mixing an aqueous caustic alkali with a chloromethyl benzoic acid containing not more than two chlorine atoms in the chloromethyl group, oxidizing said chloromethyl benzoic acid to a benzene dicarboxylic acid with said aqueous caustic alkali at a pressure sufficient to maintain a liquid phase caustic alkali and at a reaction temperature of from 150 to 400° C. whereby hydrogen formation occurs, reducing pressure buildup from hydrogen so formed by intimately contacting said liquid phase mixture with a gas containing free oxygen while at said reaction temperature, and recovering benzene dicarboxylic acid from the reaction mixture in a form selected from the group consisting of the free acid and a salt thereof.
6. A process of producing terephthalic acid which comprises converting para-mono-chloromethyl benzoic acid to terephthalic acid by oxidation with aqueous caustic alkali at a temperature of from 150 to 400° C. and under sufficient pressure to maintain said aqueous caustic in liquid phase.
7. The method as defined in claim 6, wherein a free-oxygen-containing gas is introduced into the mixture of aqueous caustic alkali and para-mono-chloromethyl benzoic acid at conversion temperature.
8. A process of producing terephthalic acid which comprises mixing an aqueous caustic alkali with para-xylylene dichloride, oxidizing said xylylene dichloride to terephthalic acid with said aqueous caustic alkali at a pressure sufficient to maintain at least a part of the water in liquid phase and at a reaction temperature of from 300 to 400° C. whereby hydrogen formation occurs, reducing pressure buildup from hydrogen so formed by intimately contacting said liquid phase mixture with a gas containing free oxygen while at said reaction temperature and recovering terephthalic acid from the reaction mixture in a

21

form selected from the group consisting of the free acid and a salt thereof.

9. A process of producing terephthalic acid from a para-di-(chloromethyl) benzene having no more than 2 hydrogen atoms of the methyl groups substituted by chlorine, which comprises converting said di-(chloromethyl) benzene to said acid by oxidation with aqueous caustic alkali in liquid phase at 300 to 400° C. whereby hydrogen formation occurs, and reducing pressure buildup from hydrogen so formed by intimately contacting said liquid phase mixture with free oxygen during said oxidation with caustic alkali and at a temperature of from 300 to 400° C.
